(57) **CLAIM**

I claim the ornamental design for tie-down strap rewinder, as shown.

DESCRIPTION

FIG. 1 is a perspective view of the tie-down strap rewinder showing my new design;

FIG. 2 is a front elevational view thereof;

FIG. 3 is a side view thereof, taken from the right of FIG. 2;

FIG. 4 is a top plan view thereof;

FIG. 5 is a rear elevational view thereof; and,

FIG. 6 is a bottom plan view thereof.

The broken lines shown in all views are for illustrative purposes only and form no part of the claimed design.
